UNITED STATES PATENT OFFICE.

THOMAS P. WHELAN, OF CLEVELAND, OHIO, ASSIGNOR OF TWO-THIRDS TO
WILLIAM GEARIETY AND EDWIN S. HENRY, BOTH OF SAME PLACE.

THREE-WAY SPLIT SWITCH.

SPECIFICATION forming part of Letters Patent No. 351,417, dated October 26, 1886.

Application filed March 22, 1886. Serial No. 196,100. (No model.)

To all whom it may concern:

Be it known that I, THOMAS P. WHELAN, of Cleveland, in the county of Cuyahoga and State of Ohio, have invented certain new and useful Improvements in Three-Way Split Switches; and I do hereby declare the following to be a full, clear, and exact description of the invention, such as will enable others skilled in the art to which it pertains to make and use the same.

My invention relates to improvements in three-way switches of the variety known as a "splitswitch;" and it consists in certain features of construction, and in combination of parts hereinafter described, and pointed out in the claims.

In the accompanying drawings, Figure 1 is a plan view of my improved three-way split switch in position for the cars to pass on the main track. Fig. 2 is a plan view showing in solid lines the switch in position connecting the front side track, and in dotted lines showing the switch connecting the rear siding. In both figures the connecting-rods are broken, and the shifting-levers and frame are shown in elevation. Fig. 3 is a top plan of the lever-frame.

A represents the main track, and B and B' the side tracks. Frogs C are arranged in the main track on either side, as shown, so that the main track always remains unbroken.

D and D' are what are known as "split rails," being in the main ordinary rails with their ends d' split or sheared off obliquely in a longitudinal direction and on a vertical line, so that these ends are wedge-shaped, the beveled faces being on the side next the adjacent frogs. The split rails are hinged at d, in the usual manner, by means of chairs; or these rails may be sufficiently long so that the rear ends may be fastened rigidly, such rails having sufficient spring or elasticity to allow the parts to move the limited distance required in operating the switch.

F are guard-rails of the ordinary construction. Connecting-rods e and e' couple the respective rails D and D' with the lower end of the respective levers E and E'. The levers are pivoted at g to the frame G. The upper portion of this frame G has slots G', between which the levers operate, and notches g', for

holding the levers in the different positions required in operating the switch. When the main track is open, the rails D and D' are held against the guard-rails F, as shown in Fig. 1, 55 the two levers standing side by side in a vertical position at the middle of the slats G'. If the forward siding is to be used, the rail D is moved against the adjacent frog, as shown in solid lines, Fig. 2. If the rear siding is to be 60 used, the rail D' is moved against the frog, as shown in dotted lines, in which case the rail D is left by the side of the guard-rail. A chain or link, H, connects the levers E and E', so that they can be separated only far enough to move 65 one split rail at a time. If, therefore, for instance, the rail D was in position against the frog for the front siding, and it was desired to use the rear siding in drawing the rail D' against the frog, the rail D would be moved 70 back against the guard-rail, by which arrangement, whenever the main track is closed, one or the other of the switches will be in position to receive the train. With the ordinary split switch the split rails are coupled together, and 75 one side of the main track is broken when the switch is in use.

With such construction, a train coming from the direction in which the side tracks extend and running into the switch when the latter 80 had been placed for the side track, the train would be likely to go onto the ground, the main track being broken. If, however, this did not occur, if the train should stop and back up, or if another train should immediately come 85 from the opposite direction, the split rail having been pried away from the track by the wheel-flanges, the train moving in the reversed direction would be sure to go onto the ground.

With my improved construction, the main 90 track, as aforesaid, being never broken, if a train should run into a switch, as in the before-supposed position of the parts, the point of the split rail would of course be pressed away from the frog and the train would pass 95 onto the main track unharmed, and if the train should back up it would either go onto the side track or keep on the main track, according to which side of the split rail the wheel-flanges passed; but in either case no harm 100 would be done.

My improved switch is no more expensive

than ordinary split switches, and it is thought that its adoption will prevent many accidents.

What I claim is—

1. In a three-way split switch, the combination, with frogs at the union of the side track and main tracks, arranged substantially as indicated, of split rails connected with the respective side tracks, levers, and connecting-rods for moving the split rails to and from the frogs, a link, chain, or suitable device for connecting the shifting-levers, and arranged substantially as described, by means of which but one split rail at a time can be moved against the frog.
- 15 2. In a three-way split switch, the combination, with a main track, side tracks, frogs, and guard-rails, arranged substantially as indicated, of so-called "split rails" connected with the respective side tracks, shifting-levers, and connecting-rods for moving the respective

split rails, a link, chain, or suitable device for connecting the shifting-levers to limit the divergence of the split rail, substantially as set forth.

3. In a three-way switch, the combination, ²⁵ with a main track, side tracks, frogs, and split rails, arranged substantially as described, of shifting-levers and connecting-rods for the respective split rails, a link or chain for connecting the levers, and a two-way frame for supporting the levers, the parts being arranged substantially as described.

In testimony whereof I sign this specification, in the presence of two witnesses, this 1st day of March, 1886.

THOMAS P. WHELAN.
